—7

Fig. 3

Fig. 4

Fig. 5

Fig. 6

FIGURE 1 is a perspective view of a boat showing my new design;

FIGURE 2 is a top plan view of the boat;

FIGURE 3 is a side elevation of the boat, the opposite side being a mirror image thereof;

FIGURE 4 is a bottom plan view of the boat;

FIGURE 5 is a front elevational view of the boat;

FIGURE 6 is a rear elevational view of the boat; and

FIGURE 7 is a slightly reduced cross-sectional view of the boat taken on the line 7—7 of FIGURE 2.

I claim:

A new and ornamental design for a boat, substantially as shown and described.
